CONTAINER

John M. Hothersall, Brooklyn, N. Y., assignor to
 American Can Company, New York, N. Y., a
 corporation of New Jersey

Application September 18, 1933, Serial No. 689,973

8 Claims. (Cl. 221—28)

The present invention relates to liquid dispensing for containers or cans which have been sealed and has particular reference to a dispensing nozzle construction for full venting of the opened can during dispensing of its liquid contents so that a steady, even, discharging stream results.

An object of the invention is the provision of a liquid container having a sealed and venting nozzle which is easily opened to condition it for pouring and which shapes and confines the discharging stream passing through the nozzle and permits an adequate supply of air entering into the can through the nozzle to displace the discharging liquid.

The invention contemplates the use of a nozzle for a liquid container which is associated with venting elements by means of which a smaller than nozzle size of discharging liquid stream is maintained during pouring to the end that the nozzle cannot be blocked by the stream but is always open for entrance of sufficient venting air to effect a smooth and rapid discharge of the liquid.

A further object of the invention is the provision of a nozzle, liquid container which is initially sealed at its nozzle and which is also supplied with an auxiliary seal or closure for the nozzle, the first seal being broken for opening of the can, the second being subsequently used to provide a reclosure.

An object of the invention is the provision of a venting nozzle for a container of the character described having an air passage extending into the interior of the can which is maintained open and free for venting during dispensing of the liquid contents.

Numerous other objects and advantages of the invention will be apparent as it is better understood from the following description, which, taken in connection with the accompanying drawing, discloses a preferred embodiment thereof.

Referring to the drawing:

Figure 1 is a perspective view of a liquid container embodying the present invention;

Fig. 2 is a perspective view of the upper end of the container showing its cover or top closure member prior to application;

Fig. 3 is an enlarged sectional view taken through the upper end of the sealed container and through the nozzle, the can being inverted, this view disclosing the dispensing of the liquid therefrom;

Fig. 4 is an enlarged sectional view of the sealed

nozzle before the can is opened, illustrating the additional auxiliary closure for the same; and

Fig. 5 is a sectional, fragmentary detail taken substantially along the line 5—5 in Fig. 3 and showing a cross section of the vent tube.

An embodiment of the present invention, as illustrated in the drawing, comprises a metallic can body 11 having a bottom 12 secured thereto in any suitable manner. The can body may be necked-in at 13 to provide a smaller diameter for the upper open end of the can. Its upper end wall is further bent outwardly and inwardly to provide a curled top edge 14 (Figs. 2 and 3).

A metallic cover member 15 may be employed for closing the can after it has been filled and such a cover member is formed with a cylindrical friction wall 16 which sets off a countersunk part of the cover and this part enters into the open reduced end 13 of the body 11 when the can is closed. The cover member 15 thus has a curved surrounding rim which encloses an annular groove 17 in which may be located a sealing gasket 18.

The outer edge of the cover rim constitutes a flange 19 from which locking lugs 21 may be extended at spaced intervals. When the cover 15 is first brought into its inserted position for closing the filled can, these lugs 21 are bent under the curled edge 14 of the body and permanently lock the cover in can sealing position.

The wall of the countersink of the cover 15 is preferably further depressed adjacent one side as at 25 and an extended or projecting curled nozzle 26 is formed in the metal in the center of the depression, the wall of the nozzle surrounding an opening 27 in the cover wall.

A vent housing 31 is secured to the cover wall and is fully inside of the can when the cover is in its can sealing position. The vent housing 40 comprises a cylindrical wall 32 merging into an outwardly extending flange 33 which is directly secured to the cover in any suitable manner as by soldering or welding.

The cylindrical wall 32 is wider on the inner side than on the side adjacent the cover rim and merges into an apertured annular inclined wall 34 which surrounds and sets off a discharge opening 35. This vent housing opening is eccentric to the cylindrical wall 32 and a vent chamber 36 is thus confined between the inner surface of the can cover and the cylindrical and inclined walls 32—34, the vent housing being at the inner side of the line or plane of the container wall or top.

A vent tube 41 (Figs. 2 and 3) is provided,

one end being inserted into and held by the wide portion of the cylindrical wall 32 and its opposite end terminating short of the peripheral edge of the cover member 15. This tube is fixedly held on the cover member, the wall 32 holding it at one end, the opposite end being formed with a lug 42 which is secured to the cover wall in any suitable manner as by spot welding.

An inexpensive yet satisfactory tube is formed by rolling a flat strip of metal into the curled form illustrated in Figs. 3 and 5, the tube walls confining an interior passageway 43, one end of which communicates with the chamber 36 of the vent housing. The opposite end terminates a short distance from the inside wall of the cam body.

The opening 27 of the nozzle 26 is adapted to be closed when the cover member is applied to the filled can and prior to using the nozzle 26 for dispensing purposes and a sealing disc 45 (Figs. 3 and 4) is used for such closing. Disc 45 is preferably formed with an outer crimped edge 46 which is adapted to be tightly clamped over the peripheral edge of the nozzle. A sealing material 47 of soft lead or the like is interposed between the nozzle and the sealing disc when a real tight joint is required.

The sealing disc is drawn and otherwise shaped as shown so that in addition to sealing the nozzle it provides for easy opening and for cooperation with a supplemental closing element as will be hereinafter fully explained. The annular crimped part 46 of the disc is merged into an upwardly extending looped wall 48, the inner leg being bent downwardly and thence inwardly as it merges into a horizontal wall 49 which extends across and seals the opening 27 of the nozzle. The wall 49 is provided with an annular score line 51 which sets off a removable central part 52, the score line providing a weakened section in the wall of the disc.

While the sealing disc 45 forms the primary or initial seal for the filled can, an auxiliary closure cap 55 is also provided which will be used to temporarily close the can after it has once been opened and during the time between opening and emptying. This cap is adapted for ready attachment to the nozzle 26 and a cap will preferably accompany each filled and sealed can so as to be available for use by the ultimate consumer of the can contents.

A satisfactory reclosure cap for this purpose is illustrated in the drawing and comprises a flexing cap formed with a raised dome or bulged center portion 56 which is surrounded with an annular grooved flange 57, the outer part of which is bent down to provide a depending skirt 58 slit at intervals to form segmental locking fingers 59 which have inwardly bent engaging ends 61. The cap 55 may also be provided with a suitable sealing gasket 62 of fibre, cork or the like.

The auxiliary cap 55 when accompanying the sealed can is in position on the nozzle 26 and it covers the sealing disc 45 at such time as shown in Fig. 4. The locking fingers 59 are held inwardly pressed and the flexing dome part 56 is in its raised position, the finger ends 61 engaging under the outer crimped rim edge 46 of the sealing disc.

The gasket 62 rests upon the upper rim of the looped wall 48 of the sealing disc. The container when received by the ultimate consumer is therefore provided with two seals, namely, the initial sealing disc 45 and the auxiliary closure cap 55.

When it is desired to dispense the liquid contents from the filled can the auxiliary cap 55 is removed, its central dome part 56 being pressed down so that the locking fingers 59 are forced outwardly to disengage their ends 61 from the edge of the sealing disc.

The score line 51 of the sealing disc is broken through in any suitable manner, any sharp instrument being adequate to break through the weakened wall 49, the removable part 52 defined by the score lines being pried out of its sealing position and thrown away. This leaves a discharge opening 65 (Fig. 3) which uncovers and makes available the nozzle opening 27.

This breaking of the disc seal constitutes an opening of the filled can which is thereupon tilted and inverted, as illustrated in Fig. 3, so that the liquid contents passes out through the discharge opening 35 of the vent housing as a confined or restricted stream of predetermined diameter. This discharging stream passes through the larger openings 27, 65.

It will be observed that the position of the discharge opening 35 relative to the nozzle openings 27, 65 and its relatively smaller diameter insures a free air space in those larger nozzle openings which is not filled by the liquid. In other words the two nozzle openings are never blocked by the discharging stream of liquid and air enters through the free space which in the present embodiment is largely in the upper part of the disc opening 65 and in the corresponding part of the nozzle opening 27.

Such air flows into the vent chamber 36. Air passes from the chamber 36 through the passage-way 43 of the tube 41 and discharges from the vent tube and passes up through the liquid in the can as bubbles (indicated in Fig. 3). This displaces the discharging liquid, there always being ample venting air for the can so that its discharging stream is even and fully confined.

It is usual to only dispense a portion of the liquid from the can at one time and after each dispensing operation the auxiliary cap 55 is removably secured into its original position on the nozzle with its gasket 62 resting upon the extended rim 48 of the sealing disc 45 and its fingers 59 holding the cap in sealing position. This provides a reclosure for the can.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A liquid container having a nozzle, and a vent housing located inside of the container and having a discharge opening of smaller diameter than the diameter of the opening of said nozzle, said housing opening being positioned within the line of the container, and offset laterally relative to the axis of the nozzle opening so that the liquid contents of the container when being dispensed is confined to a discharging stream which in leaving the housing opening passes through the larger nozzle opening, leaving a lateral space of decreasing width in the latter for entrance of air for venting.

2. A liquid container having a nozzle, and a vent housing located inside of the container and having a discharge opening of smaller diameter

- than the diameter of the opening of said nozzle, one side of said housing opening being offset laterally and positioned in vertical alignment with one side of the nozzle opening so that the liquid contents of the container when being dispensed is confined to a discharging stream which in leaving the housing opening passes through the lower part of the larger nozzle opening, leaving space at the side of the latter for entrance of air for venting and for displacing the liquid flowing from the container, the said vent housing having a chamber set off on one side of its discharge opening which receives and directs the venting air into the container.

3. A liquid container having an extended nozzle, a vent housing located inside of the container within the plane of the container wall, and having a discharge opening of smaller diameter than the diameter of the opening of said nozzle, said vent housing discharge opening being arranged eccentric to the nozzle opening, and a vent tube located inside of the container and having one end extending into said vent housing where it is spaced from the said housing discharge opening, said tube being adapted for leading air into the container to displace the liquid discharging through the said vent housing and nozzle opening when the container is being emptied.

4. A liquid container having an extended nozzle, a vent housing located inside of the container and having a discharge opening of smaller diameter than the diameter of the opening of said nozzle, the former being located eccentric to said nozzle opening, and a vent tube located inside of the container and having one end extending into said vent housing adjacent one side of the nozzle opening and spaced from one side of said housing discharge opening and adapted for leading air into the container during discharge of its liquid contents to displace the liquid discharging through the said vent housing and nozzle openings, the eccentric location of said relatively smaller discharging liquid stream relative to said nozzle allowing for passage of air at the side of said nozzle opening, partially around the discharging liquid stream and into said vent tube.

5. A liquid container having an extended nozzle, a sealing disc secured to said nozzle for liquid sealing the container, and a vent housing located inside of the container and having a discharge opening adjacent said nozzle, the axis of said discharge opening being eccentric to the axis of said nozzle, a portion of said sealing disc being adapted for removal to open the container and provide a discharge opening for said nozzle, the eccentric arrangement of said vent housing being adapted to receive air entering a substantial lateral space disposed partially around the discharging liquid stream while passing through the nozzle opening during dispensing of the liquid from the container after opening, said vent housing receiving the air and directing it into the container to displace the discharging liquid.

6. A liquid container having an extended nozzle, a sealing disc secured to said nozzle for liquid sealing the container, a vent housing located inside of the container and having a discharge opening arranged eccentric to the axis of said

nozzle and confining a chamber located on the side of said discharge opening, a portion of said sealing disc being adapted for removal to open the container and provide a discharge opening for said nozzle, and a vent tube located inside of the container and having one end connected with said housing chamber, the said chamber and tube being adapted to receive air entering at one side of the discharging liquid stream while passing through the nozzle opening during dispensing of the liquid from the container after opening, said chamber and said tube also being adapted to direct the air into the container to displace the discharging liquid.

7. A liquid container comprising a body, a cover member secured to said body, an extended nozzle formed in the wall of said cover member, a vent housing secured to the cover member and within the plane thereof and having a discharge opening of smaller diameter than the diameter of the opening of said nozzle and shaped to confine a vent chamber between the inside of said cover member and a wall surrounding said housing opening, the discharge opening of said vent housing being offset laterally relative to the axis of the nozzle, and a vent tube secured to the inside wall of said cover member and having one end held in said vent housing with its interior in communication with said housing chamber and having its opposite end terminating short of the inside wall of said body, said housing opening being adapted when the container contents is being discharged to shape and confine the discharging liquid so that the discharging stream flows out through said nozzle while permitting venting air to enter the container at one side of the discharging liquid stream and by way of said vent housing chamber and said vent tube.

8. A liquid container comprising a body, a cover member secured to said body, an extended nozzle formed in the wall of said cover member, a vent housing secured to the cover member and within the plane thereof and having a discharge opening of smaller diameter than the diameter of the opening of said nozzle and shaped to confine a vent chamber between the inside of said cover member and a wall surrounding said housing opening, the discharge opening of said vent housing being arranged eccentric to the axis of the nozzle, and a vent tube secured to the inside wall of said cover member and having one end held in said vent housing, with its interior in communication with said housing chamber and having its opposite end terminating short of the inside wall of said body, said housing opening being adapted when the container contents is being discharged to shape and confine the discharging liquid so that the discharging stream flows out through said nozzle while permitting venting air to enter the container at one side of the discharging liquid stream by way of said vent housing chamber and said vent tube, a primary closure adapted for application to said nozzle to seal the container prior to its opening, and an auxiliary closure for engaging said nozzle to temporarily seal the container after opening.

JOHN M. HOTHERSBALL.
